UNITED STATES PATENT OFFICE.

FREDERIC P. REED, OF EAST ORANGE, NEW JERSEY, ASSIGNOR, BY DIRECT AND MESNE ASSIGNMENTS, TO WATERFORD ART PAPERS, INC., OF WATERFORD, NEW YORK, A CORPORATION OF NEW YORK.

DRYING APPARATUS.

Application filed July 1, 1922. Serial No. 572,118.

To all whom it may concern:

Be it known that I, FREDERIC P. REED, a citizen of the United States, residing at East Orange, New Jersey, have invented certain new and useful Improvements in Drying Apparatus, of which the following is a clear, full, and exact description.

This invention relates to an apparatus for drying paper pulp or similar material which is spread out into a sheet or web and has for its object the arrangement and construction of the parts in such a manner that the material is quickly and thoroughly dried during its passage through a heat chamber.

An important feature of my invention relates to the provision of means whereby the web of material is guided and supported in its passage through the heat chamber, the guiding and supporting means being in the form of reels of skeleton construction which not only serve the function of guiding but also act to agitate the air so that it is more readily brought into contact with the material to be dried.

Other features and advantages will appear from the following detailed description and claims when taken in connection with the accompanying drawings in which—

Fig. 1 is a side elevation with part of the casing broken away to show the interior construction;

Fig. 2 is a section on the line 2—2 of Fig. 1;

Fig. 3 is a section on the line 3—3 of Fig. 1; and

Figs. 4 and 5 are detailed views of a reel.

Referring to the drawings, there is provided a heat chamber 1 properly supported by suitable framework, said chamber being provided with an aperture 2 through which the web of material to be dried is fed into the heat chamber, and an opening 3 out of which the dried material passes to be cut into sheets or wound up upon a core, as desired. The web of material 4 to be dried may be paper pulp or similar material which is guided by rolls 5 and 6^a towards the opening 2. The roll 5 is supported on a frame 6 which also forms a part of the support for the heat chamber. The roll 6^a is carried by an arm 7 pivoted to an upright 8 also forming a portion of the framework.

As the moist product passes through the aperture or opening 2 into the heat chamber,

it is immediately taken up by upper and lower rotating reels and conveyed through the chamber to the exit 3. These reels are carried by a frame having upright end portions 9, an upper portion 10 and a lower portion 11. A suitable inlet stack 12 for the admission of fresh air in to the chamber is provided, and likewise an outlet stack 13. For forcing the air into the chamber a Sturtevant blast may be used.

The chamber is heated to approximately 65° F. to 350° F., and any suitable means may be provided for this purpose, although preferably I use regular stock nickel chrome electrical heaters, and one of these heaters 14 is shown fastened to the upper portion of the frame 10 and another heater 15 to the lower portion 11, these heaters being bolted to the frame or fastened in any other suitable manner. Preferably a series of these heaters is provided and they are so arranged as to give equal volume of heat to both the upper and lower parts of the chamber. In order that ready access may be had to the chamber, I provide hinged doors 16. These doors fit closely to prevent any unnecessary escape of heat during the drying period.

The reels which possess the dual function of both guiding and supporting the product to be dried and agitating the air within the chamber are constructed as follows. Each reel consists of a brass head 17 having a flange 18 on its outer side by means of which it is secured to a shaft 19 through the medium of a set screw 20. The supporting surface of each reel is constructed of rods 21 of suitable diameter which fit into perforations in the heads, the ends of the rods being slightly tapped at each end to prevent their slipping out of place. Intermediate 95 the heads is a spider 22 for preventing any sagging of the rods due to the weight of the material carried and guided thereby. Each shaft 19 is shouldered at either end and revolves in a brass or bronze bearing 23 supported by the frame member 11.

For propelling the reels I prefer to use sprocket wheels fastened to the shafts and preferably the sprocket chains connecting the reels are placed alternately in pairs, that is to say, the first and second wheel is connected by a sprocket chain on one side while the second and third wheels are connected

by a sprocket chain on the other side. The initial propelling force is taken from the roll 5, the shaft of which carries at its end a sprocket 24, Fig. 3, which is connected by a sprocket chain to wheel 25 carried by the shaft 19 of the first reel within the chamber, which shaft is extended to the outside of the chamber for this purpose. This same shaft also carries a gear wheel 26 which meshes with a gear wheel 27 on the shaft 28, upon upper reel 29. There are two of these upper reels connected together by a sprocket chain for suitably guiding the product through the chamber. These reels hold the product tightly and prevent any slipping during its transit through the chamber.

The moist air is carried out of the chamber through the shaft 13 as suggested, which shaft may also be provided with an electric exhaust of known construction, the light vapor passing readily into this shaft. In order to remove the vapors which may accumulate near the bottom of the chamber, I provide a perforated conduit 30, one on each side of the chamber near the bottom thereof. These run the entire length of the chamber and discharge into the shaft 13 so that the air within the chamber is constantly renewed.

While I have shown and described a preferred embodiment of my invention, it is to be understood that variations may be resorted to without departing from the spirit thereof.

What I claim as new is—

1. In a drying apparatus for drying paper web or similar material, the combination

with a heat chamber and means for forcing air into said chamber, of means for feeding the web to be dried into said chamber, means located at both the upper and lower portions of said chamber for supplying heat, said chamber being substantially enclosed except for the ingress and egress openings for the web whereby a high temperature is maintained, and means for guiding the web within and through the chamber, said guiding means so constructed and arranged as to likewise agitate the air and cause circulation thereof through the pores of the web to be dried.

2. In a drying apparatus, the combination with a heat chamber, a frame supported therein, heat supplying means carried by said frame and reels also carried by said frame for supporting and guiding the product to be dried and for agitating the air within the chamber.

3. In a drying apparatus, the combination with a heat chamber having an entrance aperture thereto, means for feeding the product to be dried, through said aperture, into said chamber, reels of skeleton construction supported for rotation within said chamber and acting to support and guide the product and to agitate the air within said chamber, and conduits arranged near the bottom of said chamber and leading to the outside thereof, for removing the moist air.

Signed at New York, N. Y., this 29th day of June, 1922.

FREDERIC P. REED.
